[57] CLAIM

The ornamental design for a timing light, as shown and described.

DESCRIPTION

FIG. 1 is a perspective view showing our new design;

FIG. 2 is a top view thereof;

FIG. 3 is a side view thereof, the other side being identical;

FIG. 4 is a bottom view thereof;

FIG. 5 is a rear view thereof; and,

FIG. 6 is a front view thereof.

The broken line showing of a partially disclosed cord is for illustrative purposes only and forms no part of the claimed design.
